Primary Examiner—Brian N. Vinson(74) *Attorney, Agent, or Firm*—Price, Heneveld, Cooper, DeWitt & Litton(57) **CLAIM**

I claim the ornamental design for powder dispenser, as shown.

DESCRIPTION

FIG. 1 is a perspective view of the powder dispenser of my new design;

FIG. 2 is a frontal view of the powder dispenser of my new design;

FIG. 3 is a side view of the powder dispenser of my new design, taken from the right of FIG. 2;

FIG. 4 is a rear view of the powder dispenser of my new design;

FIG. 5 is a side view of the powder dispenser of my new design, taken from the left of FIG. 2;

FIG. 6 is a top view of the powder dispenser of my new design; and,

FIG. 7 is a bottom view of the powder dispenser of my new design.
